Primary Examiner — Jeffrey D Asch(74) *Attorney, Agent, or Firm* — Staas & Halsey LLP**CLAIM**

The ornamental design for a mobile communication terminal, as shown and described.

DESCRIPTION

FIG. 1 is a front perspective view of a mobile communication terminal;

FIG. 2 is a front view of the mobile communication terminal of FIG. 1;

FIG. 3 is a rear view of the mobile communication terminal of FIG. 1;

FIG. 4 is a left-side view of the mobile communication terminal of FIG. 1;

FIG. 5 is a right-side view of the mobile communication terminal of FIG. 1;

FIG. 6 is a top plan view of the mobile communication terminal of FIG. 1; and,

FIG. 7 is a bottom plan view of the mobile communication terminal of FIG. 1.

The broken lines showing of FIGS. 1-7 are for the purpose of illustrating the present invention and forms no part of the claimed design.
